UNITED STATES PATENT OFFICE.

MAX ORNSTEIN, OF NEW YORK, N. Y.

UMBRELLA AND RIB TIP THEREFOR.

Application filed October 25, 1924. Serial No. 745,924.

My invention relates to an umbrella and more particularly to the manner and means for securing the umbrella cover to the rib tips.

The general object of my invention is to provide a novel umbrella tip and a characteristic manner of securing the fabric and coordinating it with said tip.

10 The nature of my invention and its distinguishing features and advantages clearly appear as the description proceeds.

Reference is to be had to the accompanying drawings forming a part of this specification, it being understood that the drawings are merely illustrative of examples of the invention.

Figure 1 is a side elevation of an umbrella embodying my invention;

20 Figure 2 is an enlarged elevation at the end of an umbrella rib showing a portion of the rib, part of the cover and my novel rib tip as well as the manner of sewing the cover to secure it to the rib tip;

Figure 3 is a longitudinal section as indicated by the line 3—3, Figure 2;

Figure 4 is a transverse section on the line 4—4, Figure 3;

Figure 5 is a perspective view of the rib tip shown in Figures 1 to 4;

Figure 6 is an elevation of a modified tip and part of the rib, part of the cover being in section;

35 Figure 7 is a view similar to Figure 6 but illustrating a further modification of the rib tip.

In the illustrated example of my invention, the letter A indicates a handled umbrella stick; B, the umbrella cover; and C, an umbrella rib. In accordance with my invention I provide a rib tip designated 10 in Figures 1 to 4. In the illustrated example in Figures 1 to 4, the body of the rib tip 10 is rounded at the outer end and advantageously tapers in accordance with the general practice in the trade.

40 In accordance with my invention I form the rib tip 10, as illustrated in Figures 1 to 4, with an annular groove 11 near the inner end and on said rib tip near the inner end I form an annular flange 12 extending laterally outward beyond the sides of the body of the tip. The groove forms a narrow or contracted neck 13 directly adjacent to the flange 12. The rib 10 is fitted 50 to the rib C as usual and the fabric of the cover B is turned inwardly at D at each rib

tip. The cover material is brought together about the rib tip 10 at the groove 11 and flange 12. The side edges are then united by cross stitching 14, the stitches being drawn 60 tightly. The result in thus applying the cover to the described tip is that the fabric disposed about the rib tip and the stitching 14 are held tightly and present a combined annular dimension materially less than the 65 outer shoulder presented by the flange 12, the fabric and stitching at the same time entering the groove 11, the whole resulting not only in a firm securing of the cover to the rib tip but the fastening of the cover is 70 effected with facility.

In the form shown in Figure 6 the groove 11 shown in the first described form is omitted. A flange 112 is provided, however, on the inner end of the rib tip 110 and the material of the cover B is returned inwardly as at D, the same as in the first described arrangement and the doubled cover material is brought about the rib tip 110 in the same manner as previously described. The stitching indicated in Figure 6 by the numeral 75 114 corresponds in all respects with the stitching 14, the arrangement being such that said stitching and the cover jointly present an annular dimension less than that 80 of the surface presented by the shoulder at the outer side of the flange 112. In this instance the flange alone is relied upon to prevent displacement or slipping of the cover without the additional security resulting 85 from the provision of the groove 11.

In the form of the invention shown in Figure 7 the rib tip designated 210 is formed with an annular groove 211 corresponding with the groove 11 but instead of the flange 90 12 or 112, said rib tip 210 presents only an annular head 212 which does not extend laterally beyond the sides of the body of the rib tip. The provision of the groove, however, with the rib 212 results in an annular shoulder at the outer side of the head 95 212 or that side of said head adjacent the groove 211, the arrangement being such that the covering with its inner returned portion B is brought about the rib tip 210 in the same manner as previously described and the side edges of the double thickness of the covering material are held by cross stitching 214 corresponding with the stitching 14 and 110 114. The covering material with its stitching 214 crowds into the groove 211 and holds the fabric cover with substantial se-

curity particularly if an ample diameter is given the rib tip.

I would state in conclusion that while the illustrated examples constitute practical embodiments of my invention, I do not limit myself strictly to the exact details herein illustrated, since, manifestly, the same can be considerably varied without departure from the spirit of the invention as defined ¹⁰ in the appended claim.

Having thus described my invention, I claim:

As an article of manufacture, a tip for umbrella ribs adapted to be applied to the

end of a rib, said tip comprising a body ¹⁵ round in cross section and gradually of reduced diameter toward the inner end, and an annular flange on the tip at the inner end, said tip having an annular groove directly adjacent to said flange, the said flange forming one wall of said groove, the opposite wall of the groove being formed by the body of the tip at the inner end, said flange being of greater diameter than that wall of the groove formed by the inner end ²⁰ of the body.

MAX ORNSTEIN.
